UNITED STATES PATENT OFFICE

130,441

DESIGN FOR A SIGN PANEL

Frederick J. Wellmerling, Minneapolis, Minn.

Application February 21, 1940, Serial No. 90,422

Term of patent 14 years

To all whom it may concern:

Be it known that I, Frederick J. Wellmerling, a citizen of the United States and residing in the city of Minneapolis, county of Hennepin, State of Minnesota, have invented a new, original, and ornamental Design for Sign Panel, of which the following is a specification, reference being had to the accompanying drawing, forming a part thereof, wherein,

Fig. 1 is a plan view of a sign panel showing my new design; and

Fig. 2 is an end view thereof.

I claim:

The ornamental design for a sign panel, as shown.

FREDERICK J. WELLMERLING.
